UNITED STATES PATENT OFFICE.

MATHIAS REDLINGER, JR., OF FREEPORT, ILLINOIS.

LEMON-SQUEEZER.

SPECIFICATION forming part of Letters Patent No. 722,898, dated March 17, 1903.

Application filed January 4, 1902. Serial No. 88,468. (No model.)

To all whom it may concern:

Be it known that I, MATHIAS REDLINGER, Jr., a citizen of the United States of America, residing at Freeport, in the county of Stephenson and State of Illinois, have invented certain new and useful Improvements in Lemon-Squeezers, of which the following is a specification.

The object of my invention is the production of a lemon-squeezer adapted for use where lemons are used in considerable quantities; and it consists of certain new and useful features of construction and combinations of parts hereinafter fully described, and specifically pointed out in the claims.

In the accompanying drawings, which form a part of this specification, Figure 1 is a view of the left-hand end of a lemon-squeezer open embodying my invention. Fig. 2 is a section at the dotted line 2 2 in Fig. 1 of the same closed. Fig. 3 is a horizontal partial section at the dotted line 3 3 in Fig. 2 of parts there shown. Fig. 4 is a section enlarged to full size at the dotted line 4 4 in Fig. 2 of parts there shown.

Like letters of reference indicate corresponding parts throughout the several views.

A is a circular dish-shaped base provided with a discharge-spout A' and having a tubular interiorly-threaded bearing A² projecting inward through the bottom thereof.

B is a conoid-shaped closure of the base A, hinged by means of the pivot B' and lugs B² thereto.

C is a button mounted on a pivot C' on the base A and provided with a downwardly-projecting lip C², adapted to engage a counterpart projection C³ on the closure B to clamp the latter shut onto such base A while the squeezer is being operated.

D is a hollow multiple-screw-threaded rock-shaft, the threaded portion D' whereof is a counterpart of and adapted to turn and travel endwise in the tubular threaded bearing in the bottom of the dish-shaped base A of the squeezer.

E is a rotatable follower in conoidal form, having an exteriorly-threaded nipple E' integral with and projecting from the center of the inside thereof.

F is a circular nut adapted to be turned onto the nipple E'.

G G are a pair of spring-arms rigidly secured by their inner ends to the nut F and terminating at their outer ends in lugs G', 55 adapted to engage the outer end of the hollow rock-shaft D, and thereby lock the latter into rigid engagement with the rotatable follower E. The spring-arms G G pass through a slot G² in the bridge-piece G³ of the rock-shaft D to insure their synchronous rotation.

H is an interiorly-threaded transverse socket on the outer end of the rock-shaft D.

I is a lever for operating the rock-shaft D, 65 inserted into the socket H.

If the closure B in Fig. 2 be let down to the position shown in Fig. 1 and half a lemon be placed therein with its cut surface uppermost and the closure be then locked shut, as in Fig. 2, and the lever I be then turned upward, as 70 indicated by dotted lines J, the rock-shaft D will have been thereby caused to travel inward and carry with it the rotatable follower E to the position indicated by dotted lines J'. Such rotation and forward travel of the follower will have forced the half-lemon against the inside of the closure B, and thereby 75 squeezed the juice therefrom, whence it will flow out of the spout A' into any desired receptacle.

The closure B may be detached from the base A by withdrawing the pivot B' from its bearings, and by pressing the outer ends of the spring-arms G inward the rock-shaft D may be disengaged from the follower E, after 85 which it may be turned out of its bearing A² and the lever I may be unscrewed therefrom, thus leaving the parts of the squeezer in 90 knockdown for convenience in packing and shipping.

What I claim as new, and desire to secure by Letters Patent, is—

1. In a lemon-squeezer, in combination, a circular dish-shaped base, having a tubular interiorly-threaded bearing, projecting inward through the bottom thereof, a closure hinged thereto, a hollow multiple-screw-threaded rock-shaft, adapted to turn and travel endwise in the tubular threaded bearing in the base, and a rotatable follower, in 95 form of a cone, a pair of spring-arms rigidly secured, by their inner ends, to the bottom of the rotatable follower, and terminating, at their outer ends, in lugs adapted to engage 100

the outer end of the hollow rock-shaft and thereby lock the latter into rigid engagement with such follower, substantially as and for the purpose specified.

- 5 2. In a lemon-squeezer, in combination, a circular dish-shaped base, provided with a discharge-spout and having a tubular interiorly-threaded bearing projecting inward through the bottom thereof, a closure hinged thereto, a hollow screw-threaded rock-shaft, adapted to turn in the threaded bearing in the base, a follower, of conoidal form, having an exteriorly-threaded nipple projecting from the center of the inside thereof, a nut adapted to be
10 turned onto the nipple, a pair of spring-arms rigidly secured, by their inner ends, to the nut, and terminating, at their outer ends, in lugs, adapted to engage the outer end of the hollow rock-shaft and thereby lock the same into
15 rigid engagement with the rotatable follower, substantially as and for the purpose specified.
20 3. In a lemon-squeezer, in combination, a circular dish-shaped base, provided with a dis-

charge-spout and having a tubular interiorly-threaded bearing projecting inward through the bottom thereof, a closure hinged thereto, means for clamping the closure onto such base, a hollow screw-threaded rock-shaft, adapted to turn in the threaded bearing in the base, a follower, of conoidal form, having an exteriorly-threaded nipple projecting from the center of the inside thereof, a nut turned onto the nipple, a pair of spring-arms rigidly secured, by their inner ends, to said nut, and terminating, at their outer ends, in lugs adapted to engage the outer end of the hollow rock-shaft and a lever for operating such rock-shaft, substantially as and for the purpose specified.

In testimony whereof I have signed my name to this specification in the presence of two subscribing witnesses.

MATHIAS REDLINGER, JR.
